US00D889395S

(12) **United States Design Patent** (10) **Patent No.:** **US D889,395 S**
(45) **Date of Patent:** **** Jul. 7, 2020**

(54) **BATTERY**

(71) Applicant: **Integra LifeSciences Corporation**,
Plainsboro, NJ (US)

(72) Inventors: **Doug Birkholz**, Madison, WI (US);
Clay Mehnert, Madison, WI (US);
Brian Neeley, Cottage Grove, WI (US);
Steve Dieter, Oregon, WI (US)

(73) Assignee: **Integra LifeSciences Corporation**,
Princeton, NJ (US)

(**) Term: **15 Years**

(21) Appl. No.: **29/665,542**

(22) Filed: **Oct. 4, 2018**

(51) LOC (12) Cl. **13-02**

(52) U.S. Cl.

USPC **D13/103**

(57) **CLAIM**

The ornamental design for a battery, as shown and described.

DESCRIPTION

FIG. 1 is a perspective view of a battery;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines depict portions of the article that form no part of the claimed design.
